Inventor
George Le

By-

Miehle & Miehle, St. Louis

UNITED STATES PATENT OFFICE.

GEORGE LEE, OF CHICAGO, ILLINOIS.

TOILET CASE.

Application filed June 4, 1923. Serial No. 643,307.

To all whom it may concern:

Be it known that I, GEORGE LEE, a citizen of the United States, residing at Chicago, in the county of Cook and State of Illinois, 5 have invented a certain new and useful Improvement in Toilet Cases, of which the following is a full, clear, concise, and exact description, reference being had to the accompanying drawing, forming a part of 10 this specification.

My invention relates particularly to portable toilet cases such as are carried about by ladies although not limited to this use alone.

15 The main object of the invention resides in the provision of a compact, convenient, orderly, and clean toilet case which will contain all of the materials usually desired to be contained in a portable toilet case.

20 With the above object in view my invention consists in certain features of novelty in the construction, combination, and arrangement of parts by which the said object and certain other objects, hereinafter appearing, are effected, all as fully described with reference to the accompanying drawing and more particularly pointed out in the 25 claims.

In the said drawing—

30 Figure 1 is a central vertical section of a toilet case embodying my invention.

Figure 2 is a top plan view with the upper inner and outer covers, hereinafter described, broken away.

35 Figure 3 is a bottom plan view with the lower inner and outer covers, hereinafter described, broken away.

Like characters of reference indicate like parts in the several views.

40 In the said drawings 1 designates a cylindrical body member into respective ends of which are forced and secured flanged opposite wall members 2 forming with the member 1 a hollow body. One of the members 2 has an outwardly facing central compartment 3 formed inwardly therefrom, and the other wall member 2 has a plurality of outwardly facing compartments 4, 5, 6, and 7 formed inwardly therefrom. The wall 45 member 2 having the compartment 3 formed therein has a plurality of upstanding projections 8 struck therefrom and spaced around the compartment 3.

50 A closure member, comprising a flat annular member 9 and a screen 11 extending

across the opening of the member 9 and secured to the edges of the opening and forming a reticulated opening through the closure member, is releasably secured to the body by engagement of the outer edge 60 of the annular member 9 with the projections 8 and overlies the respective wall member 2 and the compartment 3 thereof. This closure member forms a powder receptacle with the compartment 3 and the said reticulated opening provides the receptacle with a reticulated opening. Complexion powder 12 may be placed in the compartment 3 by removing the closure member, and a bail 13 is pivotally secured at its opposite ends to 70 the annular member 9 so that the closure member may be conveniently removed and replaced, the bail being arranged to lie against the outer surface of the annular member 9 and to extend around outwardly 75 of the opening thereof when in normal position as shown. An inner cover 14 is hinged at 15 to the body and is adapted when in closed position to overlie the closure member and is provided with an outwardly concave central portion 16 overlying the reticulated opening of the closure member. The cover 14 is adapted when in closed position to retain a powder puff 17 over and closing 80 the reticulated opening of the powder puff, 85 the portion 16 of this cover engaging the puff. The powder puff when so retained prevents the powder from getting out of the opening of the closure member and spreading about, and the powder puff so retained is in position to have the powder distributed over the one surface thereof 90 through the reticulated opening so that the puff is charged without the powder spreading about. The convenience of this arrangement is obvious. 95

Another inner cover 18 is hinged at 19 to the body and is adapted when in closed position to overlie the other wall member 2, having the compartments 4, 5, 6, and 7 100 formed therein, and to overlie these compartments. The compartments 4, 5, 6, and 7 are designed to receive respectively a quantity of facial cream 21, a piece of complexion rouge 22, a lip stick, not shown, and a perfume bottle, not shown, and the cover 18 is adapted when in closed position to retain the lip stick and perfume bottle in the respective compartments 6 and 7, and to retain a rouge pad 23 over and against the 105 110

rouge 22 in the compartment 5. Thus these articles are retained in an orderly fashion when this cover is closed.

A pair of flanged outer covers 24 are hinged respectively at 25 and 26 to the body and are adapted when in closed position to overlap respective ends of the body and to overlie respective inner covers 14 and 18. These outer covers are releasably secured in closed position in a usual manner by means of nibs 27, formed on the body, engaging recesses 28, formed on the flanges of the covers opposite the hinge portions thereof. Mirrors 29 are mounted on the insides of respective outer covers 24, and the central portion of one mirror engages the inner cover 14, and the other mirror engages a nib 30 formed on the inner cover 18 when the covers are closed whereby to prevent movement of the inner covers out of closed position when the outer covers are closed. The mirrors 29 lie between respective inner and outer covers when they are closed and are separated from the articles carried in the case by the inner covers so that they remain clean and ready for use. Upon the opening of either outer cover the mirror thereof may be used and the materials contained in the case are accessible by opening the respective inner cover.

While I have herein shown and particularly described the preferred embodiment of my invention I do not wish to be limited to the precise details of construction shown as changes may readily be made without departing from the spirit of my invention, but having thus described my invention, I claim as new and desire to secure by Letters Patent the following:—

1. A toilet case including a powder receptacle provided with a reticulated opening, an inner cover hinged to the receptacle and adapted when in closed position to overlie said opening and to retain a powder puff over and closing said opening, an outer cover hinged to the receptacle and adapted when in closed position to overlie the inner cover whereby to prevent movement of the inner cover out of closed position, releasable means for retaining the outer cover in closed position, and a mirror arranged to lie between the covers when they are closed.

2. A toilet case including a powder receptacle provided with a reticulated opening, an inner cover hinged to the receptacle and provided with an inwardly facing enclosure portion overlying said opening and adapted to retain a powder puff over and closing said opening when the cover is in closed position, an outer cover hinged to the receptacle and adapted when in closed position to overlie the inner cover whereby to prevent movement of the inner cover out of closed position, releasable means for retaining the outer cover in closed position, and a

mirror mounted on the inside of the outer cover.

3. A toilet case including a powder receptacle comprising two separable parts, one of which is provided with a reticulated opening therethrough, an inner cover adapted when in closed position to overlie and retain a powder puff over and closing said opening, an outer cover adapted when in closed position to overlie the inner cover, and a mirror arranged to lie between the covers when they are closed.

4. A toilet case including a powder receptacle comprising two separable parts releasably secured together, one of which is provided with a reticulated opening therethrough, an inner cover adapted when in closed position to overlie and retain a powder puff over and closing said opening, an outer cover adapted when in closed position to overlie the inner cover whereby to prevent movement of the inner cover out of closed position, releasable means for retaining the outer cover in closed position, and a mirror arranged to lie between the covers when they are closed.

5. A toilet case including a powder receptacle comprising two separable parts and means releasably securing them together, one of said parts being provided with a reticulated opening therethrough, an inner cover hinged to the other part of the receptacle and adapted when in closed position to overlie and retain a powder puff over and closing said opening, an outer cover hinged to said other part of the receptacle and adapted when in closed position to overlie the inner cover whereby to prevent movement of the inner cover out of closed position, releasable means for retaining the outer cover in closed position, and a mirror arranged to lie between the covers when they are closed and mounted on one of the covers.

6. A toilet case including a body having compartments opening outwardly from respective of two opposite sides thereof, a closure member releasably secured to the body and overlying a compartment of one side of the body and forming a powder receptacle therewith and provided with a reticulated opening therethrough forming an opening for this receptacle, inner covers adapted when in closed position to respectively overlie said closure member and the compartment portion of the other side of the body for retaining a powder puff over and closing said opening and for retaining certain articles in proper relation with certain other compartments, outer covers adapted when in closed position to overlie respective inner covers whereby to prevent movement of the inner covers out of closed position, and releasable means for retaining the outer covers in closed position.

7. A toilet case including a hollow body

having outwardly opening compartments formed inwardly from respective of two opposite walls thereof, a closure member releasably secured to the body and overlying a compartment of one of said walls and forming a powder receptacle therewith and provided with a reticulated opening therethrough forming an opening for this receptacle, inner covers adapted when closed to respectively overlie said closure member and the compartment portion of the other of said walls for retaining a powder puff over and closing said opening and for retaining certain articles in proper relation with certain other compartments, outer covers adapted when in closed position to overlie respective inner covers, releasable means for retaining the outer covers in closed position, and mirrors arranged to lie between respective inner and outer covers when the covers are closed.

8. A toilet case including a body having compartments opening outwardly from respective of two opposite sides thereof, a closure member releasably secured to said body and overlying a compartment of one side of the body to form a powder receptacle therewith and provided with a reticulated opening therethrough forming an opening for this receptacle, inner covers hinged to said body and adapted when closed to respectively overlie said closure member and the compartment portion of the other of said sides for retaining a powder puff over and closing said opening and for retaining certain articles in proper relation with certain other compartments, outer covers hinged to the body and adapted when

in closed position to overlie respective inner covers, releasable means for retaining the outer covers in closed position, and mirrors arranged to lie between respective inner and outer covers when the covers are closed. 40

9. A toilet case including a hollow body having an outwardly opening compartment formed inwardly from one wall thereof and a plurality of outwardly facing compartments formed inwardly from the opposite wall thereof and provided with upstanding projections spaced around the first mentioned compartment, a closure member releasably secured to the body by engagement with said projections and overlying said first mentioned compartment to form a powder receptacle therewith and provided with a reticulated opening therethrough forming an opening for this receptacle, an inner cover hinged to the body and adapted when in closed position to overlie said closure member and retain a powder puff over and closing said opening, a second inner cover adapted when in closed position to overlie the compartments of the second mentioned wall, outer covers hinged to the body and adapted when in closed position to overlie respective inner covers whereby to prevent movement of the inner covers out of closed position, releasable means for retaining the outer covers in closed position, and mirrors mounted on the insides of respective outer covers.

In witness whereof I hereunto affix my signature this twenty-eighth day of May, 1923.

GEORGE LEE.
